CARD INDEX

Joseph H. Weatherford, Memphis, Tenn., assignor
to Mark Fakkeema, Chicago, Ill.

Application August 28, 1930, Serial No. 478,356

9 Claims. (Cl. 129—16)

This invention relates to card indexes of that type which include a frame or holder having opposed guides and a plurality of cards inter-changeably supported in said guides to have an overlapping relation relative to each other, said cards being pivotally sustained so that by swinging upwardly the cards above any desired card, the subject matter on said card will be exposed to view.

10. The objects of my invention are:—

(a) To provide a novel card index of this type in which the supporting means for the individual cards is practically indestructible and will not, therefore, be injured by removing the cards from the holder and replacing them therein;

(b) To provide a card index in which the cards themselves are so constructed that they can be typewritten upon and the typewritten matter 20 can be placed upon any desired portion of the card;

(c) To provide spacing means for the card carriers which are independent of the carriers themselves;

25. (d) To provide means for removably supporting each of the carriers independently of any other carriers;

(e) To provide means permitting ready shifting of each carrier and re-engagement in new supported position; and

30. (f) To simplify and improve the design and construction of such an index.

Fig. 1 is a perspective view of the card index embodying my invention.

35. Fig. 2 is a transverse section showing a carrier in engaged position.

Fig. 3 is an identical section showing a carrier flexed for shifting.

40. Fig. 4 is a similar section showing a modified holder section.

Fig. 5 is a sectional elevation taken as on the line IV—IV of Fig. 2.

Fig. 6 is a sectional elevation taken as on the line VI—VI of Fig. 7.

45. Fig. 7 is a sectional elevation on the line VII—VII of Fig. 6, these two latter figures showing a modification of the carrier-retainers.

Referring now to the drawing in which the various parts are indicated by numerals, the holder is preferably of sheet-metal and provided with opposed carrier-retainers, in which card carriers 10 are removably mounted. Each of these carriers is preferably a straight piece of resilient wire.

50. The holder comprises essentially an elongated, flat central portion 11, which has portions 12, extending full length on each side, bent downwardly at an angle to provide on each side a longitudinal strip diverging below the plane of

55. Integral with these strips, are the opposed carrier-retainers each formed by bending upward a strip or side 13 which extends above the level of the central portion, then bending the side inward substantially at right-angles forming a portion 14, lying in a plane slightly above the central portion 11, and thence bending the edge 15 of this portion downwardly.

60. These latter strips 15 extend slightly below the level of the central portion and are provided with notches 16, which are spaced to conform to the desired spacing of the carriers, the notches in one strip being opposite corresponding notches in the opposed strip. Preferably these notches are flared at their open sides to 65. make engagement of the carriers easier.

65. In Figures 6 and 7 the inner edge of the portion, or strip 14, is provided with corrugations 16A in lieu of the strips 15 and notches 16 hereinbefore described.

taining notches, after which it may be shifted upward or downward. Since the carriers are spaced fairly close together it is possible to depress and shift two or even more of the carriers 5 at one time.

With a holder of the kind here shown, it is feasible to group any desired number of the carriers together leaving them spaced from adjacent groups without danger of their shifting 10 out of position, as indicated in Fig. 1, by the spacing of one carrier away from a group of carriers. It will be understood that the number and spacing of the carriers in the holder and the length of the holder relative to its width 15 shown in the drawing is not intended in any way to so limit this device, as under conditions of ordinary construction and use, the relative length of the holder will be much greater and the relative spacing of the carriers much closer. 20 The independent holding of each carrier, not only accomplishes such holding purposes but it incidentally spaces the carriers and provided, as is normally the case, that the spacing of the notches in the carrier retainers is uniform, it 25 also uniformly spaces the cards so that an index number, title, or name, may be placed on the lower edge of the card and such indicia will be properly positioned and displayed for reference. The reading matter on any card is accessible by 30 simply turning up the cards above it and this operation of swinging up the cards does not wear or affect the connection of the card with its carrier for the cards merely swing and hinge about the wire carrier. 35 In the drawing the carrier-retainers are made an integral part of the holder, but they may of course be separately made and secured to the remainder of the holder.

Having described my invention, what I claim 40 is:

1. In a card index, a holder comprising an elongated central portion, having its lateral edges depressed, carrier-retainers disposed above said edges, each retainer including a longitudinal 45 strip having a notched edge depending below said central portion in the zone of the corresponding depressed lateral edge, and a plurality of flexible carriers disposed transversely across the central portion of said holder, each with its 50 ends extending into said retainers, and in engagement with notches thereof.

2. In a card index, a holder comprising an elongated central portion, having its lateral edges depressed, carrier-retainers disposed above 55 said edges, each retainer including a longitudinal strip having a notched depending edge in the zone of the corresponding depressed lateral edge, and a plurality of flexible wire carriers disposed transversely across the central portion 60 of said holder, each with its ends extending into said retainers, and in engagement with notches thereof.

3. In a card index, a sheet-metal holder, having an elongated central portion, with its lateral 65 edges depressed, carrier retainers integral with said edges, and extending above said central portion, each retainer including a longitudinal strip having a notched edge depending below said central portion in the zone of the corresponding 70 depressed lateral edge, and a plurality of flexible carriers disposed transversely across the central portion of said holder, each with its ends extending into said retainers, and in engagement with notches thereof.

4. In a card index, a holder comprising an

elongated central portion, having its lateral edges depressed, carrier retainers disposed above said edges, each retainer including a longitudinal strip having an indented edge in the zone of the corresponding depressed lateral edge, and a plurality of flexible wire carriers disposed transversely across the central portion of said holder, each with its ends extending into said retainers, and in engagement with indentations thereof. 80

5. In a card index, a sheet-metal holder, having an elongated central portion, with its lateral edges depressed, carrier retainers integral with said edges, and extending thereabove, each retainer including a longitudinal strip having an indented edge in the zone of the corresponding depressed lateral edge, and a plurality of flexible carriers disposed transversely across the central portion of said holder, each with its ends extending into said retainers, and in engagement with indentations thereof. 85

6. In a card index, a holder comprising a pair of elongated retainers spaced apart and disposed in parallelism and a central portion between and integral with said retainers; each of

100 said retainers comprising a channel having its open side facing said central portion and having its lower leg extended inward beyond the upper leg and upward to a junction with an edge of said central portion, said upper leg having a 105 downwardly projecting flange indented at substantially equal intervals, said junction edge extending upward at least level with the lower edge of said flange, and a plurality of flexible carriers disposed transversely across the central 110 portion of said holder each with its ends extending into said retainers and held in engagement with indentations thereof by the said junction edge.

7. In a card index, a holder comprising a pair 115

of elongated retainers spaced apart and disposed in parallelism and a central portion between and integral with said retainers; each of said retainers comprising a channel having its open side facing said central portion and having its 120 lower leg extended inward beyond the upper leg and upward to a junction with an edge of said central portion, said upper leg having a downwardly projecting flange indented at substantially equal intervals, and with its edge approximately level with said junction and a plurality of flexible carriers disposed transversely across the central portion of said holder each with its 125 ends extending into said retainers and held in engagement with indentations thereof by said junction edge.

8. A card index holder for use with flexible carriers, said holder comprising an elongated central portion, having its lateral edges depressed, carrier retainers disposed above said 130 edges, each retainer including a longitudinal depending flange having an indented edge below the plane of said central portion in the zone of the corresponding depressed lateral edge.

9. A card index holder for use with flexible 140 carriers, said holder comprising an elongated central portion, depressed portions outside of the lateral edges of said central portion, and carrier retainers carried by said depressed portions, each retainer including a longitudinal 145 depending flange having an indented edge below the plane of said lateral edges of said central portion in the zone of the corresponding depressed portion.
